US0D1111803S

(12) **United States Design Patent** (10) **Patent No.:** **US D1,111,803 S**
(45) **Date of Patent:** **** Feb. 10, 2026**

(54) **FASTENER**

(71) Applicant: **Illinois Tool Works Inc.**, Glenview, IL
(US)

(72) Inventors: **Logan Scott Irvine**, Chippewa Falls,
WI (US); **James S. Tisol, Jr.**,
Chippewa Falls, WI (US)

(73) Assignee: **Illinois Tool Works Inc.**, Glenview, IL
(US)

(**) Term: **15 Years**

(21) Appl. No.: **29/929,366**

(22) Filed: **Feb. 21, 2024**

(51) LOC (15) Cl. **08-08**

(52) U.S. Cl.
USPC **D8/382**

(58) **Field of Classification Search**

USPC D8/14, 349, 354, 382, 383, 385, 388,

(57) **CLAIM**

The ornamental design for a Fastener as shown and described.

DESCRIPTION

FIG. 1 is a top-side perspective view of a fastener;
FIG. 2 is a bottom-side perspective view thereof;
FIG. 3 is a front side elevation view thereof;
FIG. 4 is a rear side elevation view thereof;
FIG. 5 is a right side elevation view thereof;
FIG. 6 is a left side elevation view thereof;
FIG. 7 is a top plan view thereof; and,
FIG. 8 is a bottom plan view thereof.

The dashed broken lines in the drawings illustrate portions of the fastener that form no part of the claimed design. The dot-dash broken lines in the drawings illustrate the boundaries of the claimed design and form no part of the claimed design.

1 Claim, 8 Drawing Sheets
